MACHINE FOR MARKING ARTICLES

Cesar Bustamante, New York, N. Y.

Application January 25, 1950, Serial No. 140,445

7 Claims. (Cl. 101—41)

1

This invention relates to the marking of articles. It is customary to apply trade names, size indicia, designs, and other devices, etc. to articles such as hosiery, hats, gloves, underwear, and other articles of clothing by the "transfer" process. These "transfers" consist of impressions of the desired marking made on a carrier of sheet material with a suitable transfer material or marking composition. They are transferred to the article to be marked by placing the carrier sheet on the article and applying heat and pressure.

It is customary to supply these transfers applied in spaced relation along a paper web of indeterminate length, the transfers thus prepared being an article of commerce and being sold to the clothing manufacturer at an established price per thousand transfers. In using such transfers the clothing manufacturer customarily places the web upon the surface to be marked and applies a heated iron by hand to the upper surface of the web. This causes the marking composition of the transfer, which is on the lower surface of the web, to be transferred to the article.

To overcome the disadvantage of hand application of the transfers, various attempts have been made to apply them by machine. Thus, for example, it has been suggested to feed the strip in such a manner as to bring successive transfers into registry with the surface of a reciprocating heated plunger with the aid of electronic means or the so-called "electric eye." Such machines have the disadvantage of relatively high first cost as well as high maintenance or service cost. In another attempt to automatically feed successive transfers into registry with the applying plunger, use has been made of the difference in thickness between the paper web and the increased thickness of the web in the area of each transfer. This has proved unreliable, however, because of variation of the thickness of the web itself between successive transfers.

The present invention aims to overcome these and other difficulties in the marking of articles, and to provide a machine which can be manufactured at reasonable cost and which in a simple and reliable manner automatically feeds transfers or impressions into accurate registry beneath the applying plunger. In this specification the terms "transfer" and "impression" are used interchangeably, and, in connection with the present invention either the entire transfer or impression may be transferred to the article to be marked, or only a portion of such transfer or impression.

2

Another object of the invention is to provide an article marking machine in which the plunger may have a sufficiently long stroke to accommodate a quantity of flat articles, such as a stack of hosiery, or an article such as a hat.

Another object of the invention is to provide an article marking machine of this kind wherein the motion of the plunger does not interfere with the registry of the transfer or impression with the plunger head, so that the plunger may have a long stroke, as above mentioned, but the transfer will be placed in registry with the plunger regardless of the length of its stroke, that is, the point in its downward stroke where it engages the transfer web and presses it into contact with the work.

In accordance with the invention a carrier web of suitable transfer supporting material is advanced with intermittent motion and in steps of predetermined equal length from a printing device, such as a pair of intaglio printing rolls, from which the web receives the transfer, or impression, of transfer material, to an applying mechanism, for example, beneath a vertically reciprocable heated transfer plunger which presses the web against the article to be marked. An impression is made on the web for each feed step of the web, and an applying stroke of the plunger occurs for each feed step. Also, the distance along the web between the printing device and the transfer plunger is a multiple of the length of such feed step. Consequently, the transfers on the web are fed successively and automatically into accurate register with the transfer plunger.

35 The invention will be better understood from a consideration of the accompanying drawings which, by way of example, illustrate one embodiment thereof together with modifications of certain details. In these drawings:

40 Fig. 1 is a view of the machine principally in side elevation, but partly in section as indicated by line 1—1 of Fig. 2;

Fig. 1a shows a modified form of plunger head.

Fig. 2 is an end elevation looking from the left of Fig. 1 and with the operating clutch shown in vertical section;

Fig. 3 is a vertical section taken on line 3—3 of Fig. 1;

Fig. 4 is a vertical section taken on line 4—4 of Fig. 3;

Fig. 5 is a side view of the transfer printing roll;

Fig. 5a shows a modified form of printing roll.

Fig. 6 shows a fragment of transfer web with three transfers printed thereon;

Fig. 6a shows a fragment of web printed by the roll of Fig. 5a.

Fig. 7 is a detail section taken on line 7—7 of Fig. 1;

Fig. 8 is a similar section taken on line 8—8 of Fig. 2; and

Fig. 9 is a similar section taken on line 9—9 of Fig. 1.

Referring now to these drawings, the machine has a frame 1 having a horizontally projecting arm 2 on which rests a resilient pad 3 to support the work 4, which, for example, may be a stack of hosiery to be marked. The upper portion of frame 1 supports in a manner to be described a vertically reciprocating transfer applying plunger structure, indicated generally by numeral 5, having at its lower end a suitable head 6 with a smooth flat lower surface adapted to press the transfer web into contact with the work. Plunger head 6 is provided with suitable heating means, such as the electric heater 7 to maintain the head at the appropriate temperature to soften the marking composition of the transfer.

Plunger structure 5 comprises the head 6, a vertical rod 8 and a sliding block 9. This structure slides vertically on two guide bars 10 which are secured at their upper ends, by any suitable means, such as the screws 11, in two spaced apertures at the upper end of frame 1. The lower ends of guide bars 10 support a stationary block 12, the lower ends of bars 10 being received into this block and screws 13 fixing them thereto.

Sliding block 9 of the plunger structure is fixed to the upper end of plunger rod 8 by any suitable means, such as the screw 14, and is provided with two spaced apertures to receive stationary bars 10 and thereby slide on these rods to guide the upper end of plunger rod 8. The lower end of rod 8 is slidably guided in a central aperture in stationary block 12.

The operating mechanism for imparting vertical reciprocating movement to the transfer applying plunger 5 comprises a crank pin 15 mounted on the rear face of a gear 16 which turns on a stub shaft fixed to frame 1. A connecting rod 17 joins crank pin 15 with the rear end of a double armed lever 18 which is pivoted to frame 1 at 19. The forward end of lever 18 is connected by means of a link 20 to sliding block 9. Crank gear 16 is rotated by engagement with the teeth of a driving gear 21 which is fixed to a shaft 22 which has a bearing in frame 1 and projects through said frame to the right as viewed in Fig. 2.

Power is applied to drive the machine through a continuously rotating pulley (or gear) 23 which is keyed to the hub of a driving member 24 of a roller clutch, these two parts turning loosely on the projecting end of shaft 22 and being held thereon by collar 25. The roller clutch is of usual construction and includes a driven member 26 fixed to shaft 22 and driven from member 24 by means of a series of rollers, one of which is shown at 27. These rollers each have a biasing spring, such as spring 28, which urges the roller into wedging engagement between the internal flange of driving member 24 and the usual sloping surfaces (not shown) which are provided on driven member 26.

The clutch is provided with a control disc 29 having a series of pins projecting from its inner surface, one to engage each of the rollers 27, one of these pins being shown at 30. Control

disc 29 is provided with a single shoulder 31 arranged to be engaged by a pivoted latch bar 32 which is biased upwardly by a tension spring 33 and moved downwardly by a foot pedal (not shown) connected to latch bar 32 by means of a link 34.

When the operator depresses the pedal, thus releasing the latch bar from shoulder 31, the restraining action of pins 30 on rollers 27 is removed and these rollers are shifted outwardly by spring 28, control disc 29 rotating slightly relative to shaft 22. The outward movement of the rollers causes the engagement of the clutch and shaft 22 commences to rotate. Rotation will continue as long as latch bar 32 is held out of engagement with shoulder 31 so that transfer applying plunger 5 may be continuously reciprocated as long as desired, or if the control pedal is released promptly after actuation, latch bar 32 will reengage shoulder 31 after only a single revolution of shaft 22 and a single operation of the transfer applying plunger.

The web of transfer paper is indicated by numeral 35 and the supply of this web is afforded by a magazine reel 36 at the right of the machine as viewed in Fig. 1. Web 35 on leaving this reel passes around a take-off roller 37 on the end of a pivoted arm which is biased downwardly by means of a weight 38 so that intermittent feeding of the web may occur without requiring the acceleration of reel 36 at each step movement. After leaving roller 37, web 35 passes beneath a guide roller 39 and around a stop roller 40, thence through the printing mechanism which includes a lower or printing roll 41 and an upper or pressure roll 42.

Passing around roll 42 the web continues toward the left around a guide roller 43, thence downwardly to a fixed, but adjustably mounted, roller 44, and thence upwardly around a vertically shiftable roller 45 and downwardly across the bottom of the heated plunger head 6. Web 35 then turns upwardly again around a second vertically shiftable roller 46 and a second fixed roller 47, mounted at approximately the same level as roller 44, and thence the web is trained around a guide roller 48 from which it passes onto a take-up roller 49.

A principal feeding force is applied to the web by means of take-up roller 49 which is driven continuously in the counterclockwise direction by means of a belt 50 which is trained around a pulley 51 pinned to operating shaft 52 for the take-up roll. Belt 50 is crossed to give the correct rotation and is driven from a pulley which is fixed upon the shaft 22. The arrangement is such that continuously throughout a cycle of operation of the machine initiated by the depressing latch bar 32, take-up roll 49 is subjected to a turning force by belt 50, but the driving connection between belt 50 and pulley 51 is of a yielding nature, so that web 35 can be stopped to provide the intermittent feed of the web in a manner to be described, and when web 35 is stationary belt 50 slips on pulley 51.

The printing roll 41 is fixed on a shaft 53 which extends between the opposite side walls of a receptacle 54 for holding the marking composition, the level of this composition being indicated at 55. Roller 41 forms the left end wall of receptacle 54 and the bottom of this receptacle is formed by a doctor blade 56 which is fixed at its right end to the bottom member 57 of the receptacle, its left end being adjustable in relation to the surface of roller 41 by means

of a knurled screw 58. An electric heating device 59 is provided in proximity to printing roll 41 and preferably arranged with a thermostat to maintain the temperature of the roll within the desired limits.

Printing roll 41 is of the intaglio type and made of metal, preferably steel, and has engraved in its surface the desired marking, for example, the legend "Size 2" as shown in Fig. 5. It will be understood that as roll 41 rotates and the engraved portion passes through the marking composition within receptacle 54, and then passes the end of doctor blade 56, the surface of the roll will be scraped free of marking composition except that which is retained within the engraved recesses forming the mark or legend.

Then, as rotation continues and the engraved portion is brought into contact with web 35 at the point of tangency with pressure roller 42, the marking compound within the engraving recesses will be taken up by the fibrous or paper web 35 to form the transfer or marking. This transfer is thus mounted on the outer or upper side of web 35 as it passes around roll 42 and over rolls 43 and 44, but the transfer is on the inner side and, therefore, in contact with roll 45. Consequently, a marking composition is employed which can be maintained in the molten state within the receptacle 54 and which is adapted to pass from the molten state to the solid state during a comparatively short period of time so that the composition will have solidified by the time it reaches roller 45. It will be understood that artificial cooling means may be employed to accelerate this solidification, if desired.

Printing roll 41 is rotated by means of a chain 60 which is trained around a sprocket on shaft 53 and also around a driving sprocket of the same diameter and keyed to operating shaft 22 so that the printing roll makes one revolution for each revolution of the operating shaft.

Pressure roll 42 is arranged to turn freely on a shaft 61 which is mounted between a pair of short arms 62 which are pinned to rock shaft 63 (Fig. 1) so that by movement of this shaft pressure roll 42 can be raised or lowered to carry web 35 out of or into engagement with printing roll 41 in order to control the step feeding of the web. Integrally with arms 62 and extending in the opposite direction from rock shaft 63 are two additional arms 64 having a friction brake member 65 mounted between them at their ends. This member may be in the form of a rubber roller which is preferably fixed against rotation. When, by the rocking of shaft 63, pressure roll 42 is raised out of engagement with printing roll 41, brake member 65 is simultaneously brought into engagement with web 35 as it passes around guide roll 40, and serves to positively stop the advance of web 35, which tends to continue its movement under the feeding action of take-up roll 49.

The driving belt 50 for roll 49 commences to slip on pulley 51 at this point, but at the instant brake member 65 is raised away from the web the feeding movement of the web is resumed, thus contributing to accurate spacing of the transfers on the web. Although roll 41 serves as the printing roll, it is really a combined printing and feed roll, and serves to supplement the action of take-up roll 49 in advancing the web. This intermittent feeding movement of web 35 is controlled by means of a cam 66 which is

fixed to shaft 53 (Fig. 3) and which cooperates with a roller 67 which is carried on the end of an arm 68, the hub of which is fixed on the rear end of shaft 53 as indicated in Fig. 3.

5 The engraving on printing roll 41 which imprints the transfers on web 35 is indicated in Fig. 5 by the device "Size 2." The projection on cam 66 is mounted opposite the transfer engraving on printing roll 41, that is, on the opposite side of shaft 53 from this engraving. In the position of the parts shown in Fig. 1, the imprinting of the marking compound on the web to form the transfer is just being finished. As rotation continues, the transfer will advance approximately to the position indicated by the letter *c*, at which point roll 67 will be engaged by cam 66 and forced outwardly against the tension of a spring 69 which holds the roller in contact with the cam. This raises roller 42 away from printing roll 41 and also causes brake member 65 to engage web 35, thus stopping its motion. Web 35 remains stationary until cam 66 rotates further and allows roller 67 again to descend to the lower portion of the cam, at which point the feeding of web 35 is resumed.

20 In this way the transfer printing mechanism operates to imprint transfers on the web in equally spaced relation, as shown in Fig. 6, their spacing being equal to the circumference of printing roll 41. Transfers previously applied to the web in this manner are indicated by the letters *a* through *g*, in Fig. 1, transfer *a* being positioned substantially at the center of the head 6 of transfer applying plunger 5 and, consequently, in position to be applied to the work 4.

25 The transfer or impression applying plunger 5 is operatively associated with web guiding rolls 44, 45, 46, and 47 in such a way that the downward motion of the plunger does not displace transfer *a* (or the successive transfers) from the center of head 6, but maintains the transfer at this position during the downward stroke. This is accomplished by mounting the two removable guiding rolls 45 and 46 in such a way that they move downward with only one-half the travel of the plunger, that is, when plunger head 6 has reached the top of the work 4, the two rolls 45 and 46 will have moved down only one-half of the length of this stroke.

30 To accomplish this two stationary rack bars 10 and 11 are mounted in fixed upright position at the rear of and at opposite sides of stationary block 12 by means of the screws shown in Fig. 1, or otherwise. Also mounted on and extending downwardly from sliding block 9 are two somewhat similar rack bars 72 and 73 so that these two racks move downwardly with transfer applying plunger 5. Rollers 45 and 46 are mounted to turn freely on stub shafts 74 and 75, respectively, these shafts being fixed respectively and extending horizontally from two supporting blocks 76 and 77. Supporting blocks 76 and 77 each have a pair of enlargements 78, one above and one below a central recess in which is mounted a gear 79 which may be made integral with an extension of the respective rollers 45 and 46.

35 Enlargements 78 have recesses as shown in Figs. 7 and 8 forming shoulders bearing against the side edges of the associated rack bars. Thus, supporting block 76 is slidably guided by the two rack bars 10 and 72, and block 77 is similarly guided by rack bars 11 and 73. As shown in Fig. 1, the teeth of the gears 79 for each of the rollers 45 and 46 mesh with the teeth of the respective pairs of racks. Consequently, as racks 72 and 73

move downwardly with plunger 5, these two gears 19 will rotate and carry their respective blocks 16 and 17 (and rolls 45 and 46) downward by one-half of the travel of plunger 5.

By making roller 44 adjustable on rack bar 70, the effective length of web 35 between the point of printing the transfer upon it and the center of the heated head 6 of the transfer plunger can be adjusted so as to center a transfer on head 6 at the end of each feed step. It will be understood that this effective web length is a multiple of the length of a single feed step. In order to mount roller 44 in an adjustable position on the back of rack bar 70, the shaft on which roller 44 turns is fixed to the upper end portion of a sliding block 80. This block is flanged along each side to enable it to be guided by the rack bar. Block 80 is also slotted as shown at 81 to receive a thumb screw 82, the inner end of which is tapped into an aperture in the rear face of rack bar 70.

The maximum height of the work is, such, for example, as a stack of hosiery depends upon the angular length of the high portion of cam 66, and in Fig. 1 the line 83 indicates the height of the bottom of plunger head 6 above pad 3 when the cam follower roller 67 passes onto or off of the projection or high portion of cam 66.

In operating the machine, the operator folds back, or removes, the uppermost article of the stack 4 after it has been marked, thereby exposing the article below. Hence, the height of the stack continually decreases and accordingly the length of the stroke of plunger 5 increases, the automatic registration of a transfer on the center of plunger head 6 continuing regardless of this change in length of stroke. It will be understood, however, that it is not necessary for a transfer or impression to be advanced into registry with plunger 6 before the downward stroke of the plunger commences; ordinarily, the transfer will be fed forward to registering position with respect to the plunger just prior to the plunger head reaching line 83 on its downward stroke, so that the transfer will be ready to be placed in the correct position on the work.

Assuming that the top of the stack is below the maximum height line 83 and that plunger head 6 has just left the bottom of its stroke, it continues upward, and until it reaches line 83 web 35 is held stationary. At this point, follower roller 67 rolls off of the high portion of cam 66 and a step feed of the web commences. This feeding movement continues while the plunger head 6 proceeds upward to the top of its stroke and then again descends to line 83. At this point, roller 67 again passes onto the high portion of cam 66, thus stopping the step advance of the web, the succeeding transfer having been moved into registry with plunger head 6 ready to be applied to the next article of the stack.

The motion of plunger head 6 above maximum height line 83 of the work affords time for the operator to fold back, or feed a new article into position beneath the plunger; also this motion enables large articles, for example, as hats to be placed under the plunger.

In the modified form of transfer printing roll 41a shown in Fig. 5a, instead of engraving the roll in the exact outline of the transfer or impression to be applied to the goods, this roll is engraved over an area 84 which is somewhat larger than the overall dimensions of the marking, which is to be applied to the article. This results in printing or applying corresponding areas on web 35a

in the same spaced relation as the markings on web 35 as shown in Fig. 6. The engraving of the area 84 on the surface of printing roll 41a is preferably in the form of two series of diagonal lines, 5 the lines of each series being parallel with each other and at an angle to the lines of the other series, after the manner of the engraving of an intaglio printing roll for producing newspaper "cuts." This results in the areas 85 on the web 10 being printed not with a continuous coating of the marking composition but in a series of fine uniform dots of such material.

In utilizing this form of transfer or impression, the lower surface of the heated head 6a of the transfer plunger structure 5 (Fig. 1a) is provided with suitable type 86 which projects below the bottom surface of this head. This type may, for example, be arranged to form the same size indicia, namely "Size 2" as was described in connection with the preferred form of the apparatus. Hence, when this type presses the transfer web 35a and one of the transfer or impression areas 85 into engagement with an article to be marked, that portion of the transfer material of area 85 20 will be transferred to the article, leaving the remainder of the transfer material on the web. Otherwise, the operation of the apparatus with this modified form of printing roll is exactly as described above.

30 By means of the present apparatus, the transfers or impressions are fed automatically into registry with the transfer applying plunger by means of a simple and inexpensive mechanism not involving complications or requiring high 35 maintenance cost. Also, the automatic registry of the transfers and the plunger head, is independent of the length of the plunger stroke, within the range of the apparatus.

It will be understood that other changes in the 40 construction and arrangement of the apparatus than the modification described herein, may be made without exceeding the scope of the invention as set forth in the appended claims.

I claim:

45 1. In a machine for marking articles comprising a reciprocating plunger for transferring transfer material from a web onto the article to be marked, feeding mechanism for feeding said web beneath said plunger, said mechanism operating to advance the web with intermittent motion and in steps of predetermined equal length, transfer material printing mechanism operating to produce an impression of such material on said web in advance of said plunger, and mechanism for actuating said printing mechanism and for moving said plunger to transferring position at each feed step of said web, the distance along said web between the point of production of the impressions thereon and the center of said reciprocating plunger being a multiple of the length of a single feed step of said web, whereby successive impressions on said web are automatically advanced into registry with said plunger for each transfer stroke thereof.

60 2. A machine for marking articles as set forth in claim 1 in which the feed and printing mechanisms are actuated alternately with the movement of the plunger.

65 3. A machine for marking articles as set forth in claim 1 in which the transfer material printing mechanism comprises a printing roll.

4. A machine for marking articles as set forth in claim 1 in which the web feeding mechanism includes four web guiding rollers associated with

75 the transfer plunger, a stationary roller and a

movable roller being arranged on each side of the plunger, the web passing first around one of said stationary rollers, thence around the first movable roller, thence across the plunger face, thence around the second movable roller to the second stationary roller, and said movable rollers being actuated by said plunger and having one-half the travel of said plunger, whereby the movement of the plunger does not interfere with the registry with the plunger of the successive impressions carried by the web.

5. A machine for marking articles comprising a reciprocating plunger for transferring transfer material from a web onto the article to be marked, feeding mechanism for advancing said web beneath said plunger in a step-by-step movement with alternate periods of motion and dwell, a rotary printing mechanism for producing on said web in advance of said plunger successive impressions of transfer material, means for operating said printing mechanism during each period of motion of said web, and mechanism for actuating said plunger during each dwell period of said web.

6. A machine for marking articles as set forth in claim 5 wherein the web is advanced by the feeding mechanism in steps of predetermined equal length, and the apparatus is constructed and arranged so that the distance along the web between the point of production of the impressions thereon and the center of the reciprocating plunger is a multiple of the length of a

25

15

20

30

single feed step by which successive impressions on the web are automatically brought into registry with the plunger.

7. A machine for marking articles as set forth in claim 6 in which the web feeding mechanism includes four web guiding rollers associated with the transfer plunger, a stationary roller and a movable roller being arranged on each side of the plunger, the web passing first around one of said stationary rollers, thence around the first movable roller, thence across the plunger face, thence around the second movable roller to the second stationary roller, and said movable rollers being actuated by said plunger and having one-half the travel of said plunger, whereby the movement of the plunger does not interfere with the registry with the plunger of the successive impressions carried by the web.
